UNITED STATES PATENT OFFICE.

GEORGE G. POWERS, OF LOS ANGELES, CALIFORNIA.

HYPODERMIC NEEDLE.

1,217,630.

Specification of Letters Patent. Patented Feb. 27, 1917.

Application filed November 22, 1916. Serial No. 132,781.

To all whom it may concern:

Be it known that I, GEORGE G. POWERS, a citizen of the United States, residing at Los Angeles, in the county of Los Angeles, State of California, have invented new and useful Improvements in Hypodermic Needles, of which the following is a specification.

This invention relates to hypodermic syringes and the like; and particularly to hypodermic needles and the combination including the needle and other parts of the syringe. And it is included within the objects of this invention to provide a construction including a double ended reversible needle; to provide an effective and simple mounting for the needle; and to provide a compact and efficient combination of needle, syringe barrel or cylinder, and piston.

I describe a preferred form of syringe embodying my invention, and illustrate the same in the accompanying drawings, in which: Figure 1 is a section showing my improvement; Fig. 2 is an enlarged section showing the needle mounting; Fig. 3 is an enlarged section showing the needle and its mounting collar alone; and Figs. 4 and 5 are sections showing modified needle mountings.

In the drawings the numeral 10 designates a cylinder or barrel, which may be of any desired size, configuration and design. In the form of apparatus here illustrated, this cylinder or barrel is of comparatively small diameter and is provided with a plunger piston 11, which has a central longitudinal bore 12. A handle 13 is mounted upon the end of the plunger, and handles 14 are mounted upon the barrel, for purposes of manipulation. The plunger or barrel, or both, may be provided with the usual measuring marks; and may otherwise be conformed and arranged in any usual manner.

At the end of the barrel I provide a head member 15 which is screw threaded at 16 into the barrel; a suitable washer 17 being provided inside the head as a limit stop to the movement of the plunger. A fluid-tight gasket or washer 17^a is provided between the end of the barrel and the flange 18 of the head; and the exterior surface of the head may be knurled or otherwise suited for manual engagement and rotation, as illus-

trated at 19. The head has a projecting screw-threaded nipple 20 upon which the cap 21 screw-threadedly engages. This cap 21 is internally screw-threaded and has a recess 22 below the screw-threads adapted to receive the mounting collar 23 of the needle 24. The construction of this mounting collar is most clearly shown in Fig. 3. I show a needle 24 of any suitable type, having an internal bore, and open at both its opposite ends. The mounting collar 23 comprises an outside ring or ferrule 25 of relatively hard unyielding metal, and an interior filling 26 of relatively soft yielding metal, such as lead or lead alloy. This filling may be packed, pounded or pressed into the ring 25 around the needle, without the necessity of melting the filling and pouring it into the case, thus obviating any liability of destroying the proper temper of the needle. When the filling is properly placed it closely and tightly surrounds the needle and the ring 25 fits tightly around the filling. I prefer to make the filling of three pieces of soft metal; a ring piece 26^a having its ends conically recessed, and two conical pieces 26^b fitting into the conical recesses. The whole is pressed together endwise in a suitable press, etc.; and the exterior of the needle may be serrated or otherwise roughened at 24^a to provide a good holding surface. When the mounting collar is in position, as shown in Fig. 2, the end 20^a of nipple 20 presses against one end of the filling, without pressing against the hard metal ring 25, and the bottom 22^a of the recess 22 in the cap also presses against the filling, preferably without pressing against the ring 25. By this means the filling is compressed longitudinally, thus expanding the filling against the hard metal ring and contracting it around the needle; so as to hold the needle tightly in place and make a fluid-tight joint between the soft metal and the needle. At the same time, the part 20^a makes a fluid tight joint with the soft metal of the filling.

The head member 15 has an internal bore 15^a through which the needle extends, and the cap 21 has an internal bore 21^a in which the needle fits more or less snugly; the cap extending in conical formation, so as to support the needle. In this regard it may be said that the end of the cap may be of any

desired configuration or character, so as to support the needle in any manner desired. The inner end of the bore 21^a is conically enlarged so as to facilitate the passage of the 5 needle through the bore.

In practice I preferably place the mounting collar 23 on the middle portions of the needle, and, in some instances at least, nearer one end of the needle than the other; so that 10 the needle may be reversed to provide either the long or short projecting part. In either case, the unused end of the needle projects back into the barrel and into the bore 12 of the plunger. In this manner I provide for the 15 accommodation of a very long needle to be exposed and used only when desired; and make this accommodation without making the barrel or plunger excessively long. The long end of the needle may be, if desired, as long 20 as the interior bore 12 of the plunger. There is a further advantage in having the needle project into the barrel; in that any foreign solid matter which would clog the needle (under the great pressure used) stops at its 25 entry at the inner end of the needle, where it may be readily removed. And, furthermore, the inner end of the needle is quite removed from the lower end of the barrel, at which lower end any foreign solid matter 30 tends to collect.

The needle mounting is a feature to which I particularly call attention. It will be noted that the mounting collar 23 is, to all practical intents and purposes, a permanent 35 part of the needle; although it may be removed from the needle, or moved longitudinally thereon, without much trouble. This particular mounting may be used in other forms of syringes. I have already stated that 40 the end of cap 21 may be of any desired configuration; and another typical configuration of this cap is illustrated in Fig. 4, where the end portion 21^b of the cap is curved, and holds the needle in curved configuration, 45 rather than straight. In Fig. 5 I have shown a construction in which the nipple 20 is extended, as shown at 20^b, and curved, so as to hold the needle pointing transversely to the length of the barrel.

50 Although I have described my device in some detail, I do not thereby limit my invention to the specific forms set forth. Modifications and variations (of which the described modified forms are typical) may be

made within the scope of the claims without 55 exceeding my invention.

Having described a preferred form of my invention, I claim:

1. In a device of the character described, a barrel, a hollow piston therein, and a hollow 60 needle mounted on the end of the barrel and projecting inwardly into the barrel and into the hollow piston.

2. In a device of the character described, a barrel, a hollow piston therein, a hollow 65 needle having a mounting collar on its middle portion, and means at the end of the barrel for holding the needle by clamping its collar, one end of the needle projecting into the barrel and into the hollow piston. 70

3. In a device of the character described, a hollow needle, and a mounting collar therefor embodying an exterior ring of relatively hard metal and a core of relatively soft metal surrounding the needle and with- 75

4. Mounting means for a hypodermic needle or the like, embodying a mounting collar on the needle comprising an exterior ring of relatively hard metal and a core of 80 relatively soft metal around the needle within the ring, and a needle holder embodying two members screw-threadedly engaging each other and adapted to press oppositely against the ends of the soft metal of the 85 needle collar.

5. In a device of the character described, a barrel, a hollow piston therein, a needle holder on the end of the barrel comprising a member forming a barrel head and a cap 90 screw-threaded on said member, a needle extending longitudinally through the said member and said cap and projecting into the barrel and into the hollow piston, a mounting collar on the needle held between the 95 said member and cap, said collar embodying an outer ring of relatively hard metal and an inner filling of relatively soft metal, the soft metal filling being held and compressed longitudinally between said member and 100 said cap.

In witness that I claim the foregoing I have hereunto subscribed my name this 17th day of November 1916.

GEO. G. POWERS.
